UNITED STATES PATENT OFFICE.

LEO O. MILLER, OF DETROIT, MICHIGAN.

LOCK FOR MILK CABINETS.

Application filed April 10, 1922. Serial No. 550,971.

To all whom it may concern:

Be it known that I, LEO O. MILLER, a citizen of the United States of America, residing at Detroit, in the county of Wayne, 5 and State of Michigan, have invented certain new and useful Improvements in Locks for Milk Cabinets, of which the following is a specification, reference being had thereto in the accompanying drawings.

10 This invention relates to locks or latches for closures and more particularly to a lock especially adapted for milk cabinets and the like. An object of the invention is to provide a device which is simple in construction, cheap to manufacture and efficient in operation, and wherein the arrangement is such that the closure will be latched in closed position so that it may be readily opened to place articles in the cabinet and 15 will operate upon the closing of the closure to lock the same in closed position against unauthorized opening of the closure from the outside but may be readily released and re-set from the inside to permit the closure 20 to be again opened from the outside. A further object is to provide a device in the construction of which sheet metal stampings may be employed and an arrangement secured whereby the device may be readily 25 installed by an unskilled workman, and wherein are secured certain other new and useful features, all as hereinafter more fully described.

With the above and other ends in view, 30 the invention consists in the matters herein-after set forth and more particularly pointed out in the appended claims, reference being had to the accompanying drawings in which—

40 Fig. 1 is a perspective view of a device illustrative of an embodiment of the invention and showing the same as applied to the wall of a cabinet or receptacle and to a closure therefor with the closure held in unlocked position thereby;

45 Fig. 2 is a similar view illustrative of the operation of the device with the closure locked in closed position, and

50 Fig. 3 is a horizontal section through a cabinet and its closure, and showing the device in edge elevation.

Houses are commonly built with a milk cabinet framed into a wall thereof with an inside and an outside door for the cabinet, 55 thus providing a receptacle for milk bottles

into which these bottles may be placed from outside the wall and from which receptacle the bottles may be removed from inside the house. This arrangement does not however, 60 prevent pilfering of the bottles as the entrance to the cabinet may be freely opened from the outside and the object of the present invention is to provide means whereby the outer door is automatically locked against being opened from the outside and 65 whereby, by a proper setting of the device, the outer door is held in closed position but free to be opened so that free access may be had to the cabinet from the outside for the purpose of placing articles therein 70 and when so placed and the outer door closed, said door will be automatically locked to prevent access to the cabinet from the outside. The device as shown has been de- 75 signed primarily for use upon milk cab- 80 inets but it will be readily understood that said device may be applied to other recep- 85 tacles having doors and the purpose of which is such as to make the use of such a device desirable.

As shown in the drawing, 1 indicates the wall or framing of a cabinet which is set in the wall of a house and is provided with an outside door 2 and an inside door 3. The device illustrative of the invention comprises 85 a hook or latch device of any suitable con- 90 struction indicated as a whole by the nu- 95 meral 4 and secured to the door 2 adjacent the free edge thereof, and a co-operating catch device carried by the wall 1 and in- 100 dicated as a whole by the numeral 5. The catch device 5 comprises a sheet metal base plate 6 secured in any suitable manner to the wall 1, as by screws 7 or the like, and formed integral with one end of this plate 105 is an outstanding lug or strike plate 8 adapt- 90 ed to be engaged by the dog or hook 9 of the latch device 4, said hook 9 being formed to engage over the lug 8 and hold the door closed when swung to closed posi- 110 tion, said hook being swung upon its pivot 10 and normally held in lowered position by means of a spring 11 so that its inclined outer end 12 when brought into engagement with the lug 8 will raise the hook or dog and permit it to snap over the upper edge of the lug when the door reaches closed position, to securely lock the door closed, as shown in Fig. 2. This dog or latch 9 is released by pressing upon the tail piece 13 110

of the dog against the action of the spring 11, raising said dog out of engagement with the lug 8.

In order to set the device so that the dog 9 will hold the door 2 closed against its being accidentally swung open by the wind or otherwise, and to hold the dog out of engagement with the lug 8 so that said door may be opened from the outside to place articles in the cabinet, a setting device is provided comprising a sheet metal plate 14 formed with longitudinal slots 15 and 16 through which slots extend pins or rivets 17 for securing the slide 14 to the face of the base plate 6 to slide longitudinally thereon, said slide being formed with an out-turned integral member or portion adjacent the inner end of the slide and forming a lifting foot 18 adapted to engage the inclined end 12 of the dog 9 and lift said dog when the slide is moved longitudinally toward the lug 8, said slide being so positioned that said foot 18, will move in a horizontal plane slightly above the plane of the upper edge of the lug and pass over said lug after the dog has been lifted out of engagement with the lug. A slot or opening 19 is provided in this foot 18 to receive the engaging point of the dog 9 when said dog is lifted thereby and thus, as shown in Fig. 1, the door will be held closed by the engagement of this pointed end of the dog within said opening 19 with the dog out of engagement with the lug 8 and said foot positioned directly above the said dog. The slide 14 is moved in one direction by means of a coiled spring 20 attached at one end to an outturned ear 21 on the slide and at its opposite end to a like ear 22 on the base plate 6, and to assist in moving said slide manually against the action of this spring, said slide plate is formed with an outturned end portion at its end opposite that provided with the foot, forming a handle 23.

When the parts are in the position shown in Fig. 1, the door 2 is held in closed position by the engagement of the dog 9 with the foot 18 of the slide but an outward pull upon the door will move the slide against the action of the spring 20 thus moving said slide outward to the limit of its movement the length of which is determined by the length of the slots 15 and 16, and as the inner end of the slot 15 is formed with an upwardly and inwardly inclined portion 24 and the slot 16 has an inwardly and downwardly inclined end portion 25, when the pins 17 enter these inclined end portions of the slots, said slide will be tilted, its outer or foot end portion moving outwardly and downwardly, and its inner end moving outwardly and upwardly, thus disengaging said foot from the dog 9 just prior to the slide reaching the outer end of its movement. Therefore when the device is set

by the movement of the slide toward the door and the consequent lifting of the dog and its engagement with the opening in the foot on the slide, the door may be opened from the outside by an outward pull on the door, so that articles may be placed in the cabinet from the outside.

Immediately upon the release of the dog from the slide by an outward swing of the door, the slide will be returned to normal position with its guide pins 17 in the outer ends of its slots, by the action of the spring 20 and therefore when the door is again closed after the articles have been put in the cabinet, the dog 9 will engage over the upper edge of the lug 8 and the door will be locked thereby against being opened from the outside. When it is desired to again set the device so that the door may be opened from the outside, it is only necessary for the operator to open the inner door 3 and, by means of the handle 23, move the slide against the action of the spring to lift the dog 9 out of engagement with the lug 8 and engage said dog within the opening in the foot on the slide, the spring then acting to hold the door closed until such time as the door is again swung outwardly against the action of the spring, which swinging movement will move the slide and by reason of the inclined end portions of the slots in the slide, disengage said foot from the dog, releasing the door.

The construction of the device as shown, is simple and cheap to manufacture as the several parts may be sheet metal stampings, and the simplicity of construction also adapt it for installation by an unskilled person.

While I have shown and described the device as applied to a milk cabinet, it is obvious that the same may as readily be applied to outside or wall doors of ice boxes and the like, or adapted to other uses where a locking device of this character may be desirable, and that changes in the construction may be made to adapt the same to the particular use to which it is to be put. It is therefore to be understood that changes falling within the scope of the appended claims are contemplated and that I do not limit myself to the construction shown.

Having thus fully described my invention what I claim is:

1. A device of the character described comprising a movable member adapted to be secured to a closure, a fixed member adapted to be secured to the wall of a receptacle to be engaged by the member on the closure and lock the closure in closed position, and means operable from within the receptacle to disengage said member on the closure from said fixed member and to be engaged by said member on the closure to hold said closure in closed position and permit the closure to be opened from the outside.
2. A device of the character described

comprising means for locking a closure in closed position including a locking dog and means within a receptacle closed by said closure for operating said dog to release the closure and to be engaged by said dog to hold said closure in closed position and permit the opening of said closure from outside said receptacle.

3. A device of the character described comprising a pivoted dog, a fixed member to be engaged by said dog to lock a closure, and means to engage beneath said dog to raise said dog out of engagement with said fixed member and with which dog is adapted to engage for detachably holding said closure in closed position.

4. A device of the character described comprising a pivoted dog adapted to be secured to a closure, a lug adapted to be secured to a receptacle wall to be engaged by said dog and lock the closure in closed position, a slide operable from within the receptacle to disengage said dog from said lug and to be engaged by said dog to hold said closure in closed position and permit the closure to be opened from the outside, yielding means for moving said slide in one direction, and means for moving the slide toward said dog against the action of said yielding means.

5. A device of the character described comprising a pivoted dog adapted to be secured to a closure, a fixed lug adapted to be secured to a receptacle wall to be engaged by said dog, a slide to engage and release said dog from engagement with said lug, and means guiding said slide to impart thereto a motion for releasing the same from engagement with said dog when said closure is opened.

6. A device of the character described comprising locking members adapted to be secured to a receptacle and its closure within the receptacle to be brought into locking engagement by the closing of said closure, and setting mechanism for setting the locking means to permit the opening of the closure, said setting mechanism comprising means adapted to be moved into engagement with the locking member on the closure to release said member from the locking member on the receptacle and to engage the member on the closure and hold said closure in closed position, said setting mechanism being adapted when in set position to be moved by the opening of the closure to release said setting means from said locking member on the closure, to release the closure.

60 7. A device of the character described comprising a pivoted locking member to be secured upon the inner side of a closure, a fixed member adapted to be secured upon a wall of a receptacle within the receptacle

to be engaged by the pivoted member upon the closing of the closure, and setting mechanism within the receptacle, said setting mechanism comprising a slide having a portion adapted to be interposed between said pivoted and fixed members to disengage the same and engage said pivoted member with said slide, and yielding means for resisting the movement of said slide.

8. A device as characterized in claim 7, and including means for guiding said slide out of engagement with said pivoted member when said slide is moved by the opening of said closure.

9. A device as characterized in claim 7, and including means for guiding said slide out of engagement with said pivoted member when said slide is moved by the opening of said closure, said yielding means being operative to move said slide in position to the opening movement of the closure, and means for moving said slide against the action of said yielding means into engagement with said locking member on the closure.

10. A device of the character described comprising a dog adapted to be pivotally attached to the inner side of a closure, a lug adapted to be secured to a wall of a receptacle to be engaged by said dog and lock the closure in closed position, a slide to be supported by the wall of the receptacle for movement toward said dog and over said lug, said dog being provided with an inclined end portion to be engaged by said slide and lift said dog out of engagement with said lug, said dog and slide being formed to come into holding engagement, means for guiding said slide to disengage said slide from said dog when said slide is moved by the opening of the closure, and a spring to resist the longitudinal movement of said slide in one direction.

11. A device of the character described comprising a dog pivotally attached to a closure, a sheet metal plate secured to a wall of a receptacle closed by said closure, said plate being formed with an outstanding lug adapted to be engaged by said dog, a slide comprising a plate formed with longitudinal slots having inclined end portions, an outstanding foot on said slide formed with an opening to be engaged by said dog, said dog being formed with an inclined end portion adapted to be engaged by said slide to lift said dog out of engagement with said lug, and a spring to yieldingly move said slide longitudinally away from said dog.

In testimony whereof I affix my signature in presence of two witnesses.
